(57) **CLAIM**

The ornamental design for bicycle kickstand foot as shown and described.

DESCRIPTION

FIG. 1 is a top perspective view of a bicycle kickstand foot, depicted in use on a bicycle, according to one embodiment of the present disclosure;

FIG. 2 is a top perspective view of the bicycle kickstand foot of FIG. 1, depicted removed from the bicycle;

FIG. 3 is a top perspective view of the bicycle kickstand foot of FIG. 1;

FIG. 4 is a top plan view thereof;

FIG. 5 is a left side elevational view thereof;

FIG. 6 is a front elevational view thereof;

FIG. 7 is a right side elevational view thereof;

FIG. 8 is a rear elevational view thereof;

FIG. 9 is a bottom plan view thereof;

FIG. 10 is a top perspective view of the bicycle kickstand foot, according to another embodiment of the present disclosure;

FIG. 11 is a top plan view of the bicycle kickstand foot of FIG. 10;

FIG. 12 is a left side elevational view thereof;

FIG. 13 is a front elevational view thereof;

FIG. 14 is a right side elevational view thereof;

FIG. 15 is a rear elevational view thereof; and,

FIG. 16 is a bottom plan view thereof.

The broken lines shown in the drawings are for the purpose of illustrating environment and form no part of the claimed design.

1 Claim, 6 Drawing Sheets
